[57] CLAIM

The ornamental design for a computer keyboard, substantially as shown and described.

DESCRIPTION

FIG. 1 is an isometric view of a computer keyboard showing our new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a right side elevational view thereof;

FIG. 7 is a right side elevational view thereof with the bottom supporting legs in the extended position.

The left side view is substantially the same as the right side view except that the leftmost double key shown in FIG. 6 and 7 is replaced by two keys.

FIG. 1

FIG. 2

FIG. 3

FIG. 5

FIG. 4

FIG. 6

FIG. 7
